UNITED STATES PATENT OFFICE.

CHARLES KOSMIN, OF ARLINGTON HEIGHTS, ILLINOIS.

DITCHING-MACHINE.

1,023,156.

Specification of Letters Patent. Patented Apr. 16, 1912.

Application filed August 10, 1910. Serial No. 576,506.

To all whom it may concern:

Be it known that I, CHARLES KOSMIN, citizen of the United States, residing at Arlington Heights, in the county of Cook 5 and State of Illinois, have invented certain new and useful Improvements in Ditching-Machines, of which the following is a specification.

My invention relates to a ditching or excavating machine, and the invention has 10 for its object to provide the several new and improved constructions, arrangements and apparatuses in ditching or excavating machines which will be hereafter described and 15 claimed.

One of the objects of the invention is to so arrange the instrumentalities used in 20 making the excavation that, when desired, the trench may be wider at the top than the bottom.

A further object of the invention is to 25 provide a new and improved conveyer by means of which the spoils may be deposited at either side of the machine as may be desired.

The invention is illustrated in a preferred embodiment in the accompanying drawings, wherein—

Figure 1 is a side elevation of the machine, 30 Fig. 2, a sectional elevation taken on line 2—2 of Fig. 1, looking in the direction of the arrows; Fig. 3, a sectional plan taken on line 3—3 of Fig. 1, showing certain parts broken away; Fig. 4, a detail section on 35 line 4—4 of Fig. 3; Fig. 5, a vertical cross sectional view taken on line 5—5 of Fig. 3, looking in the direction of the arrows; Fig. 6, a fragmentary elevation, on an enlarged scale, of the upper end of the boom and digging chains, and Figs. 7 and 8, views in perspective of devices employed for cutting into the bottom and sides, respectively, of the ditch. Fig. 9 is a detail view.

Like characters of reference indicate like 45 parts in the several figures of the drawings.

The machine as shown consists of a carriage 30 which is adapted to be propelled by suitable driving means; a boom pivotally mounted on a shaft 75 over which run certain digging chains, digging or earth cutting apparatus and scoops; a conveyer being provided which runs transversely of the carriage and is placed so as to receive the spoils from the digging chain scoops and 50 discharge the same at one side or the other of the ditch, as may be desired; and certain

other mechanisms which make up the complete machine but which as they are not directly here concerned need not be described in detail.

The boom or pivoted frame which carries the digging chains preferably is made up of the two side plates 68, formed with the upper and lower flanges 69 between which side plates are mounted the main upper sprocket wheel 70 and the lower main sprocket 71. Over these sprockets runs the main digging chain 72 to which are secured in alternate arrangement the cutting devices or diggers 73 and the scoops or buckets 74. The boom is pivotally supported at its upper end on a shaft 75 carried in bearings 76 on the frame members 77; shaft 75 carrying the upper main sprocket 70 and also, at each side of the boom an upper sprocket 78 over which runs an auxiliary chain 79 which at its lower ends runs over a sprocket 80 mounted on the boom. The auxiliary chains 79 carry cutting devices 81 which make the cuts along the sides of the trench. The three digging chains are driven by a chain 82 which runs over a sprocket 83 on shaft 75. The chain 82 is driven by any suitable driving mechanism.

The outer end of the boom may be raised 85 and lowered and the boom held in the desired angular position by any suitable means.

Preferably, as stated, a main digging chain 72 is employed to which is attached a series of digging tools 73, one of which is shown in detail in Fig. 7. This device consists of a blade 135, which is secured to the link pivots of the chain by means of the preferably integral forked members 136. 95 The blade 135 is preferably toothed and its function is to cut into the earth transversely of the trench. On the auxiliary, or side chains 79, are cutting devices for cutting the earth at the sides of the proposed trench, one of these devices being shown in Fig. 8 100 and consisting of a member 81, provided with lugs 138, by means of which it may be secured to a link pivot of the chain; a blade 139, and, preferably, a bracing strap 140 adapted to be secured to the next adjacent link pivot. The sprockets over which chains 79 run at the upper end of the boom are 105 preferably mounted on shaft 75 so as to be adjustable to and from the side plates 68. 110 The shaft 75 has a feather 141 and the sprockets 78 are provided with set-screws

142. The purpose of this arrangement is to permit chains 79 to be spread at the upper end of the boom by which blades 139 are given an inclination which will cause them, 5 when desired, to cut a trench which will be wider at the top than the bottom.

The buckets or scoops 74, with which the main digging chain is provided, dig up the earth cut and loosened by the devices 73, 81, 10 and deliver it on the transverse conveyer.

The conveyer, designed to deliver the spoils from the buckets to one side or other of the trench, as may be desired, is preferably constructed as follows: A frame work 15 is provided, consisting of the two overlapping frames 155, 156 which are clamped together by the screws 157, wing-nuts 158 and clamps 158^a (Figs. 3 and 4), and their overlapping parts formed with slots 159 (Fig. 20), enabling the framework to be slidably carried on the rods 160, supported on brackets 161 on the frame work 30 of the carriage. The frames 155, 156 carry sprocket wheels 162 over which run the chains 163 carrying 25 the endless apron 164. The purpose of making the frame work in two parts is to enable the effective length of the conveyer to be varied, the chains 163 at the shorter adjustments of frames 155, 156 running slack, 30 as shown in Fig. 2. The purpose of making the frame work movable on rods 160 is to allow the same to be moved from one side to the other of the machine, according to whether the spoils are to be delivered to one 35 side or the other of the ditch.

On shaft 104 (Fig. 5) are loosely mounted two bevel gears 165, 166 which are adapted to be brought into mesh with a bevel gear 167 on a short shaft 168 arranged under the 40 frame of the carriage. Shaft 168 has rigid therewith the sprocket 170 over which runs a chain 171, driving a sprocket 172 on a shaft 173, which shaft carries the pair of sprockets 175 meshing with and driving the 45 chains 163 of the endless conveyer. The bevel gears 165, 166 are engaged by the forked ends of a lever 176 which may be set at three different positions on the segment 177. This arrangement enables the endless 50 conveyer to be driven in either direction or to stand idle, as may be desired.

It will be observed that the conveyer as a whole is movable bodily from side to side and that in order to make this shift it is 55 only necessary to drive the chains in the direction desired. The conveyer is in effect a

floating conveyer which takes its position at one side or the other of the machine, according to which direction the chains are driven. Preferably a board 178^a is provided at the 60 side of the conveyer opposite to the buckets to prevent the dirt from spilling off the conveyer. It will be understood that the digging chains move in the direction indicated by the arrows in Figs. 1 and 6. The flanges 65 69 of the side plates of the boom provide bearings for the main chain.

I claim:

1. In apparatus of the character described, the combination with supporting 70 means of a boom, a main digging chain carried by said boom, auxiliary chains at the sides of said main chain, provided with cutting blades which bear against and cut the sides of the ditch and means for spreading 75 the auxiliary chains at their upper ends so as to cause the cutters thereof to make oblique cuts.

2. In apparatus of the character described, the combination with supporting 80 means of a boom, a main chain on said boom, provided with transverse cutting blades adapted to cut transversely of the ditch, and with scoops to remove the spoils, auxiliary chains, provided with cutting blades arranged so as to bear against and cut the sides of the ditch, sprockets over which said 85 several chains run, and means for shifting the relative positions of the auxiliary chain sprockets at one end of the boom, substantially as and for the purpose described. 90

3. In apparatus of the character described, the combination with a carriage and excavating apparatus supported thereon, of guide rods arranged longitudinally of said 95 carriage, a conveyer upon which the excavating apparatus delivers comprising a frame consisting of two overlapping frame members and means for securing the same together, said frame members being slotted 100 so that said frame is slidable transversely of the carriage upon said guide rods, sprockets carried on the ends of said frame, endless chains on said sprockets, an endless apron on said chains, and a shaft extending 105 longitudinally of said carriage and provided with sprockets engaging with said chains; and means for driving said shaft.

CHARLES KOSMIN.
